UNITED STATES PATENT OFFICE.

WILFRED A. HARE, OF DETROIT, MICHIGAN.

UNDERFEED STOKER.

1,361,988.

Specification of Letters Patent. Patented Dec. 14, 1920.

Application filed December 7, 1918. Serial No. 265,698.

To all whom it may concern:

Be it known that I, WILFRED A. HARE, a subject of the King of England, residing at Detroit, in the county of Wayne and State of Michigan, have invented certain new and useful Improvements in Underfeed Stokers, of which the following is a specification, reference being had therein to the accompanying drawings.

10 The present invention relates to improvements in boiler furnaces and more particularly to furnaces of the underfeed type having a retort and inclined grate bars with one end supported adjacent the retort. The object of the invention is to provide certain new and useful features in the construction and arrangement of parts whereby a more positive feeding of fuel is secured, a better distribution of air is provided and parts prevented thereby from being burned out, a new and beneficial construction and operation of grate bars obtained, and an efficient ash and clinker discharge provided.

25 With these and other ends in view, the invention consists in the matters hereinafter set forth and more particularly pointed out in the appended claims, reference being had to the accompanying drawings, in which—

Figure 1 is a longitudinal vertical section 30 through a furnace embodying features of the invention;

Fig. 2 is a transverse vertical section through the same;

Fig. 3 is a sectional view similar to Fig. 35 2 illustrative of the operation of grate bars and dumping grate;

Fig. 4 is a front elevation of the furnace with parts shown in section substantially upon the line IV—IV of Fig. 1;

40 Fig. 5 is a front end elevation of grate bars and dumping grate, showing operating mechanism therefor and a retort and pusher in section substantially upon the line V—V of Fig. 1;

45 Fig. 6 is a sectional detail through a portion of the front end portion of a retort and hopper throat;

Fig. 7 is a detail showing a twyer block in elevation;

50 Fig. 8 is a similar detail of a twyer block of the opposite twyer;

Fig. 9 is a detail showing a series of grate bars in end elevation with a twyer block in section; and

55 Figs. 10, 11, 12 and 13 are perspective views of twyer-block sections.

While a construction of furnace is shown in which a retort is located adjacent one wall of the furnace with grate bars extending laterally from one side of the retort, it will be understood that such arrangement is merely illustrative of the invention which may be embodied as well in a furnace having a duplicate set of grate bars and mechanism at the other side of the retort, and further changes in the construction and arrangement of parts may be made within the scope of the appended claims.

As shown in the drawings, 1 is a suitable feed box bolted or otherwise secured to the front plate 2 of the front wall of the furnace and forming a continuation of the retort 3 which has a throat or extension 4 opening through said wall. The feed box 1 has an opening in its upper side forming the throat 5 of a hopper 6 and secured to and closing the front end of the feed box is a casing 7 forming a steam cylinder and chest, within which cylinder is a piston 8 operated in the usual manner by steam or other fluid pressure admitted through inlet ports and passages in the chest. A suitable piston rod 9 is operated by the piston, and this rod is connected in any suitable manner to the forward end of a pusher slide 10 which forms a movable bottom for the retort 3. Obviously, any suitable power device may be connected to the pusher slide 10 for reciprocating the same upon supporting ribs 11 provided therefor upon the feed box and the side walls 12 of the retort.

The forward end of the slide 10 is formed with a pusher head 13 providing a reciprocable pusher table 14 of a length to close the throat of the hopper when the slide is 95 in its rearmost position and a vertical pusher wall 15 behind which the coal from the hopper falls when the slide moves forward, the head 13 having the table 14 and wall 15 forming a reciprocable pusher. This table 100 has upwardly projecting edge ribs 16 formed with inclined inner sides forming a continuation of the inner inclined faces of the throat 5, which faces are slightly undercut to receive these ribs, the joint between the table 105 and side walls of the throat being thus formed above the upper face of the table to prevent the joint from becoming clogged and to assist in preventing fine coal and dust from passing therethrough. To prevent fine 110 coal and dirt from passing through the joint between the upper face of the table at its

2

forward end and the hopper throat, said throat is recessed to receive a block 17 which fits loosely in the recess and rests upon the face of the table. Close contact of the block 5 with the table is maintained by gravity as the table slides back and forth beneath the hopper throat and thus fine particles of coal are prevented from working through the joint at the forward end of the table, the 10 block acting as a gravity scraper.

To provide a non-reciprocable plate or table to receive the coal as it falls from the hopper behind the pusher wall 15, said wall is provided with a slot or opening 15^a centrally disposed and adjacent the upper face of the pusher slide 10 and of a length equal to the width of said face. Projecting through this slot is a plate or gravity table 18 pivotally supported at 19 forwardly of 15 the path of movement of the pusher and provided with a downturned rear end or rib 20 to engage the upper surface of the pusher slide 10, said plate being of a length to extend inwardly beyond the throat of the hopper 25 per with its inner end held by gravity in contact with the face of the slide. To close the slot in the wall 15 so that fine particles of coal can not work through above the plate 18, a plate or block 21 is loosely attached to 30 the rear side of the wall 15 by means of a bolt 22 passing through a vertically elongated slot in the plate with the lower edge of said plate held by gravity in contact with the upper surface of the plate 18. The 35 joints between the reciprocable pusher and adjacent non-reciprocable parts are thus closed to prevent fine coal and dust from sifting through and clogging of the pusher is prevented so that it will always slide 40 freely. The plate 18 also provides a non-reciprocable table to receive coal from the hopper and from which it is pushed rearwardly into the retort by the pusher, the coal fed in being thus prevented from being 45 dragged back beneath the hopper by a return or forward movement of the pusher slide, and the danger of clogging being eliminated due to the fact that said plate 18 is pivotally supported at its forward end so that the 50 weight of coal falling thereon holds its rear end in firm contact with the surfaces of the pusher slide.

It is common practice to set the pusher slide and retort at a slight inclination in 55 the direction of its length to a horizontal plane so that the coal will feed into and along the retort more readily but such construction has certain structural and manufacturing disadvantages which are overcome 60 in the present construction by forming the upper surface of the pusher slide 10 in a plane which is inclined in the direction of the length of the slide, to its plane of reciprocation which is horizontal, and such construction is permissible as the receiving plate 65

18 is held by gravity in contact with said upper surface of the slide at all times. Further, this construction reduces the weight of the slide and at the same time provides the necessary rigidity and strength as it is 70 thickest at its forward end where strength is required and comparatively thin at its rear end.

The retort 3 is supported within the furnace by parallel walls 23 spaced from 75 the sides 12 of the retort and connected by end walls 24 adjacent the front and back walls of the furnace, said walls 23 and 24 forming a wind box 25 into which air under pressure is admitted through a suitable conduit 26, and its admission is controlled by a suitable shutter or damper 27 of any desired form which may be operated by means of a push rod 28 extending through the furnace front and provided with a hand 80 hold for convenient manipulation by the attendant.

The upper ends of the walls 23 are each provided with an outwardly projecting flange 29 forming seats for twyers 30 and 90 31 which rest thereon and the upper edges of the retort walls 12, spanning the space between said walls and the walls 23 of the wind box from the front to the back walls of the furnace. In the construction shown, 95 this flange 29 of one of the walls also forms a seat for the upper ends of a series of hollow grate bars 32 and 32^a, the other wall of the wind box being located adjacent a side wall 33 of the furnace, but it will be understood that in furnaces having a double set of grate bars, the wind box may be located at the center of the furnace chamber with like twyers and sets of grate bars seated upon said flanges 29. With the wind box 100 located as shown, the twyer 31 forms means for conducting air to the retort at one side for maintaining combustion and for cooling the twyer, said twyer comprising a wall plate 34 and a twyer block 35, said block being formed of a plurality of sections 36 and 37 secured together by bolts or rivets 38, there being a plurality of the sections 36 placed face to face between two end sections 37 to form a block. Each section 36 has ribs 115 39 projecting laterally from a central rib or web 40 and a face portion 41 the full width of the section, said face portions together forming a continuous twyer wall when the sections are secured together, the 120 ribs 39 on one section meeting the adjacent sections to form air passages 42 opening through the face portion or wall 41. The ribs 39 extend inwardly and curve upwardly within and toward the top of the 125 wall plate 34, so that air from the wind box is forced to ascend to the top of the twyer before it can enter the passages 42 and pass cut into the retort through these passages which open through the wall 41 of the 130

twyer, thus cooling the upper end of the twyer block and wall plate. The end sections 37 of each twyer block are also provided with ribs 39 forming, together with 5 the ribs of adjacent sections 36, passages 42, and these end sections are also provided with hooks 43 at their upper ends and hooks 44 at their lower ends, these hooks being provided to engage rounded projections 45 10 and 46 on the wall plate 34 and retort wall 12, respectively. When the several sections forming each block 35 are secured together by bolts 38, said blocks are set into place upon the retort walls 12 and the hooks 43 15 engaged over the projections 45 on the wall plate. The blocks are thus detachably held in place so that they may be quickly and easily lifted out for replacement and repair, but are firmly held in place for use by their 20 hooks, any movement of the lower ends of the blocks toward the wall plate being prevented by lugs 47 on the end sections 37 which lugs are provided to engage corresponding lugs or projections 48 on the wall 25 plate. These blocks 35 are thus made up in sections to facilitate manufacture and are formed to interlock with the wall plate and retort wall in such a manner that they will not become displaced in use but are always 30 readily detachable for replacement or repair.

In a similar manner, the twyer 30 is made up of a series of blocks 49 and each block comprises a series of intermediate sections 50 and end sections 51, which sections are 35 secured together by bolts or rivets 52. The several sections are provided with laterally extending ribs 53 which, when the sections are secured together meet adjacent sections and form air passages 54 which open 40 through the face wall 55 of the twyer block. This face wall is extended upward and outward forming a projecting portion 56 adapted to overlie the upper ends of the grate bars 32 and 32^a. The end sections 51 are 45 each formed with a vertical wall or web 57 having a lug 58 at the lower end thereof projecting inwardly of the block to underlie the ends of the grate bars and said end sections are also formed with hooks 59 to engage 50 rounded projections 60 on the wall 12 of the retort, similar to the hook 44 and projection 46 of the twyer blocks 35 and retort wall, respectively. The twyer blocks 49 are thus formed to rest upon the flange 29 of the wall 55 of the wind box, and the adjacent wall of the retort, spanning the space between said walls and forming air passages therethrough connecting the wind box and the upper ends of the several hollow grate bars, the several 60 passages 54 in the twyer block forming conduits communicating with said passages and opening into the retort. An unobstructed passage is thus provided by the several twyer blocks for conducting air into the 65 grate bars and both twyer and grate bars

are effectually cooled thereby and prevented from burning out.

The series of grate bars is made of fixed and movable bars alternating either individually or in pairs each having substantially the same construction with the exception that the fixed bars 32 are provided with lugs 61 near their lower ends to engage a rib 62 on a suitable fixed supporting wall 63, which wall with the adjacent side wall 23 of the wind box, forms a closed air chamber 64 beneath the grate bars. The movable bars 32^a are each provided with a socket at its lower end to receive a longitudinal rib 65^a on a rocker-bar 65 supported in a suitable bearing on the side of the wall 63. The grate bars are each rectangular in cross section being preferably formed of two channel members bolted together to form a hollow bar which is open at its upper end and closed at its lower end, an outlet opening 66 being provided at the lower side of each bar near its lower end to connect the passage through each bar with the chamber 64 so that air under pressure from the wind box 25 will 90 circulate through the twyer 30 and the hollow grate bars 32 and 32^a to the chamber 64 and from thence upward between the grate bars to maintain combustion of the coal thereon. To cause a portion of the air to 95 pass to the extreme lower end of each bar and thus cool the same, a deflector 67 is provided opposite the opening 66 to divide the air stream and deflect a portion thereof into the lower end of the bar.

A dumping or ash grate 68 is provided at the lower end of the grate bars 32 and 32^a to receive the ash and clinker therefrom and this grate is formed of a series of movable sections pivotally attached to and supported 100 at their upper ends by ears 69 on the rocker bar 65. The lower ends of the grate sections are carried by links 70 pivotally connected to the sections at one end and to arms 71 at their opposite ends, which arms are secured 110 upon a shaft 72 mounted in suitable bearings on the supporting wall 63. The outer end of the shaft 72 extends through the front wall and front plate 2 of the furnace and is provided with a sector 73 engaged by a worm 114 74 mounted in a suitable bracket 75 on said plate and forming a bearing for an operating shaft 76 which extends past the side wall of the furnace and has a formed end 77 for the engagement of an operating crank (not shown) by means of which the shaft and worm may be turned to turn the shaft 72 and thus swing the grate members 68 about their pivotal support on the rocker bar 65. The size of the opening or space between the end of the grate and the side wall 78 of the furnace may thus be adjusted or the grate swung down to the position shown in dotted lines in Fig. 3 for the purpose of dumping the ash and clinkers.

Mounted in the inner side of the wall 78 is a suitable bracket or support 79 forming a bearing for a shaft 80 upon which is mounted a series of toothed wheels 81 loosely 5 mounted on the shaft to turn freely thereon and form a clinker bar or crusher. The grate members 68 are continuously operated by the rocking movement of the rocker shaft 65 by which they are carried and thus a 10 reciprocating motion toward and from the crusher 81 is imparted to the grate which works the ash and clinker downwardly thereon and through the space between the downwardly curved lower ends of the grate 15 sections and the clinker bar. By reason of the support of the grate sections at their lower ends by the links 70, these sections have an outward and downward movement toward the clinker bar so that any clinker 20 caught between said clinker bar and downwardly curved ends of said grate members will be crushed by such movement, and the toothed members 81 being free to turn on their shaft will assist in such crushing action 25 and at the same time will be turned thereby so that a different portion of their surface will be presented to extreme heat above the grates, thus preventing the burning out of the clinker grinders or members 81. These 30 clinker grinders also take the wear which would otherwise disintegrate the furnace wall and the continued reciprocation of the ash grate, prevents the accumulation of hot ash and clinker, without attention on the 35 part of the operator.

Motion is imparted to the rocker-shaft 65 from the pusher slide 10 by means of a rocker 82 pivotally mounted intermediate its ends upon a suitable fixed bracket 83 40 secured to a side wall of the retort, one end of said rocker being connected by a link 84 to the pusher slide, and the other end of said rocker being connected to an arm 86 on the end of the shaft 65, by a connecting rod 45 87, all as shown in Fig. 5.

As the pusher is reciprocated by the piston 8 to feed coal into the retort, this reciprocation imparts a rocking movement to the rocker 82 and it in turn, through its 50 connecting rod 87, imparts a swinging movement to the arm 86, rocking the rock-shaft 65 back and forth continuously, which movement raises and lowers the movable grate bars 32^a by reason of the engagement of the rib 65^a on the rock-bar with the sockets therefor on the bars, and also continuously reciprocates the ash grate members 68. As the movable grate bars 32^a are carried at their lower ends by the rocker-bar 65 and 60 rest upon the flanged upper end of the wall 23 of the wind box, free to slide thereon, these movable grate bars are not only raised and lowered by the turning of the rocker-bar 65 but a limited reciprocating movement is imparted thereto which movement

greatly assists in spreading and working the coal down upon the grate and in preventing the clogging of the air passages between the grate bars. As the movable grate bars are independent of the twyer 30, said twyer remains stationary upon the retort so that the coal therein is not disturbed and the twyer forms a smooth continuation of the retort wall over which the coal passes freely. By continuing the wall 55 of the twyer sections 75 to overlie and bear upon the ends of the grate bars by gravity, fine coal is prevented from working into the spaces between the ends of the bars and the twyer and hindering free movement of the bars or clogging 80 the passages, and the upper ends of the bars are covered thereby to protect the same from the heat and present a smooth rounded surface.

Obviously, changes may be made within 85 the scope of the appended claims, in the form, construction and arrangement of parts without departing from the spirit of the invention and I do not therefore limit myself to the particular embodiment shown. 90

What I claim is:

1. In a furnace stoker, the combination of a pusher for feeding fuel into the furnace, means for reciprocating said pusher, a hopper, a non-reciprocable gravity table 95 beneath the hopper to receive fuel therefrom, and from which table the fuel is forced by the reciprocation of the pusher thereover, and a pusher slide reciprocable with the pusher and in contact with which 100 the table is held by gravity.

2. In a furnace stoker, the combination of a pusher slide extending into the furnace, a pusher head on the slide having an opening disposed centrally of the slide, a hopper 105 beneath which the head is reciprocable, a non-reciprocable gravity table extending longitudinally of the slide through said opening with its inner end portion only held by gravity in contact with the upper surface 110 of the slide, and means for reciprocating the slide and head.

3. In a furnace stoker, the combination of a pusher slide, extending into the furnace, a pusher head, a hopper beneath which the 115 head is reciprocable, a gravity table pivotally supported independent of said slide and head and extending beneath the hopper with its free end held in contact with the slide by gravity, and means for reciprocating the 120 slide and head.

4. In a furnace stoker, the combination of a pusher slide extending into the furnace and having a pusher head with an opening between the slide and head, a non-recipro- 125 cable pivotally supported table extending longitudinally of the slide through said opening with its free end held by gravity in contact with the upper face of the slide, and means for reciprocating the slide. 130

5. In a furnace stoker, the combination of a hopper, a pusher slide extending into the furnace and provided with a head reciprocable with the slide beneath the hopper, 5 said slide having an opening adjacent the head, a table pivotally supported at one end and independently of the slide and head and extending longitudinally of the slide through said opening with its free end resting upon the upper surface of said slide, and means for reciprocating the slide.
6. In a furnace stoker, the combination of a hopper, a pusher slide extending into the furnace and provided with a head reciprocable with the slide beneath the hopper, 15 said slide having an opening adjacent the head, a table pivotally supported at one end independently of the slide and extending longitudinally of the slide through said opening with its free end resting upon said slide, and a member beneath the head held by gravity upon the upper surface of the table to close the opening between the head and the upper side of the table.
7. In a furnace stoker, the combination of a hopper, a pusher reciprocable beneath the hopper and having a member provided with a plane upper surface to close the throat of the hopper, and a member at one 30 side of the throat and free to move toward and from said plane upper surface and held by gravity in contact with said surface to close the space between said pusher member and hopper throat.
8. In a furnace stoker, the combination of a hopper, a pusher slide extending into the furnace, a head on the outer end of the slide providing a horizontal closure for the hopper and a vertically extending wall between 40 the closure and slide, said wall being formed with a slot adjacent the slide, a table pivotally supported at one end with its free end extending through the opening in said wall and resting upon said slide, a closure for 45 said slot carried by the outer side of said wall and held in engagement with the upper surface of the table by gravity, a vertically guided gravity block extending across in contact with the upper surface of the 50 head forming the closure for the hopper and at the forward side of the throat of the hopper, and means for reciprocating the pusher slide and head.
9. In a furnace stoker, a reciprocable 55 pusher slide having an upper surface inclined in the direction of its length throughout the major portion thereof to its plane of reciprocation to provide an inclined coal carrying surface, and means for reciprocating the pusher slide.
10. In a furnace stoker, a horizontally reciprocable pusher slide extending into the furnace and having an upper fuel carrying surface throughout that portion thereof 65 which extends into the furnace, which sur-
- face is inclined downwardly toward its inner end in the direction of the length of the slide, and means for reciprocating said pusher slide.
11. In a furnace stoker, the combination of a retort having an extension projecting through a wall of the furnace, a hopper mounted upon the extension and formed with a throat having vertical guides at the forward side thereof, a gravity block in said 70 guides forming the forward side of said throat, a pusher slide forming the bottom of the retort and having an upper surface inclined in the direction of its length to its plane of reciprocation, a head on the outer 75 end of said pusher slide forming a closure for the hopper throat and upon which the gravity block rests, said head having an opening adjacent the upper surface of the slide, a member pivoted within the extension 80 and extending through said opening with its inner end resting upon the upper surface of the slide, and means for reciprocating the slide and head.
12. In a furnace, the combination of a retort having a side wall, a series of hollow 85 grate bars supported at one end adjacent to said wall, and a twyer upon said wall formed of a plurality of detachable blocks into which the open ends of said grate bars 90 open, said twyer blocks being formed with portions to overlie and portions to underlie said ends of said bars, whereby the twyer blocks are detachably interlocked with the 95 bars and held in place thereby.
13. In a furnace, the combination of a retort having a side wall, a series of hollow 100 inclined grate bars supported at their upper ends adjacent said wall and free to move relatively thereto, a hollow stationary twyer on said wall inclosing and detachably 105 interlocked with the open upper ends of said bars, and a rocker bar adjacent the lower ends of the grate bars for imparting thereto a rising and falling movement at 110 their lower ends and a sliding movement at their upper ends within said twyer.
14. In a furnace, the combination of a wind box having side walls, a retort in the upper portion of said box, with its side wall 115 spaced from the side wall of the wind box, a twyer spanning the space between said side wall of the box and said side wall of the retort, a series of hollow inclined grate bars with their upper ends resting upon said 120 side wall of the wind box and opening into the twyer, said twyer overlying and underlying said open ends of said bars and held in place thereby, said twyer being also formed with a series of passages opening through a 125 wall of the twyer into the retort, and means for imparting movement to said bars to move the same relatively to said twyer.
15. In a furnace, the combination of a series of hollow grate bars, a support for one 130

- end of said bars upon which they are free to move, a retort having a side wall, a twyer formed to detachably engage the retort wall and support and span the space between 5 said wall and support, said twyer being formed with portions to overlie and portions to underlie the ends of said grate bars, and means for imparting movement to said bars.
- 10 16. In a furnace, the combination of a series of hollow grate bars, a support for one end of said bars upon which they are free to move, a retort having a side wall spaced from said support, and a twyer de- 15 tachably interlocked with said side wall of said retort and spanning the space between the retort and support and overlying and resting by gravity upon the ends of said grate bars upon said support, and means for 20 imparting movement to said grate bars.
17. In a furnace, the combination of a series of hollow grate bars, a support for one end of said bars upon which they are free to move, a retort having a side wall, 25 and a twyer formed with a wall forming a continuation of the retort wall and having openings therein, said twyer being formed of a plurality of sections each having ribs meeting the adjacent sections to form air 30 passages leading to said openings in the wall of said twyer, certain of said sections being formed with means to detachably engage the retort wall and with portions to underlie said grate bars, said sections to- 35 gether forming a curved passage connecting the open ends of the grate bars with the space below the twyer.
18. In a furnace, the combination of a series of hollow grate bars, a support for 40 one end of said bars upon which they are free to move, a retort having a side wall spaced from said support, and a twyer formed of a plurality of independently de- 45 tachable blocks free to move rotatively upon said retort wall and having projections to interlock with said wall, said twyer blocks each being also formed with a portion to overlie and to be held by gravity in contact with the upper surfaces of said ends of said 50 bars, and means for imparting movement to said grate bars.
19. In a furnace, the combination of a furnace wall, a retort extending parallel with and spaced from said wall, a twyer 55 forming a continuation of the side wall of the retort and having projections to detachably engage said retort wall, and a member secured to the furnace wall and having pro- 60 jections to detachably interlock with projec- tions on said twyer.
20. In a furnace, the combination of a furnace wall, a retort having a wall extending parallel with and spaced from said furnace wall, a hollow twyer spanning the space 65 between said furnace wall and said wall of
- said retort and comprising a member se- cured to the furnace wall and a series of hollow twyer sections formed to detachably interlock with said member and with the adjacent wall of the retort to span the space 70 therebetween and form an upward continuation of the wall of the retort.
21. In a furnace, the combination of a furnace wall, a retort extending parallel with and spaced from said wall, a hollow 75 twyer spanning the space between said furnace wall and said retort and comprising a member secured to said wall and a series of blocks each formed of a plurality of sec- 80 tions and each provided with means to inter- lock with the wall member and the adjacent wall of the retort, each section being formed with ribs to meet the adjacent sections and form air passages opening through the wall of the twyer and extending upwardly within 85 the twyer.
22. In a furnace, the combination of a furnace wall, a retort extending parallel with and spaced from said wall, a hollow 90 twyer spanning the space between said furnace wall and said retort and comprising a member secured to said wall and a series of blocks each formed with a wall forming a continuation of a wall of the retort and pro- 95 vided with means at one side adapted to interlock with the wall member and with means at the other side adapted to engage the adjacent wall of the retort, each block being also formed with air passages open- 100 ing through the wall of the twyer and ex- tending upwardly within the twyer.
23. In a furnace, the combination of a furnace wall, a wind box adjacent said wall, 105 a retort within said wind box with its side walls spaced from the side walls of the wind box, a wall member secured to the furnace wall, twyer members spanning the space between said wall member and retort wall and detachably interlocked with said mem- 110 ber and wall, a series of hollow grate bars supported at one end by a wall of the wind box, a twyer spanning the space between 115 said ends of said grate bars and the adjacent wall of the retort, said twyer being formed with a passage connecting the space between said wind box wall and retort with the open ends of said grate bars, and with an upwardly extending and outwardly 120 curved wall forming a continuation of the retort wall and having twyer openings open- 125 ing into said passage, and said twyer wall being extended over and resting by gravity upon the upper ends of said bars with said ends extending into said twyer and free to move longitudinally relatively thereto, said twyer being also formed with portions underly- 130 ing said ends of said bars and over- lying the said side wall of the wind box, and means for moving said bars.
24. In a furnace, the combination of a

- series of inclined grate bars, a rocker bar adjacent the lower ends of said bars for operating the same, an ash grate supported at one end by and connected to said rocker bar to be operated thereby, and means for supporting the opposite end of said ash grate adapted to permit actuation of the ash grate by said rocker bar.
25. In a furnace, the combination of a series of inclined grate bars, a rocker bar for operating said bars and supporting their lower ends, an ash grate at the lower end of said bars to receive ash and clinkers therefrom and supported at one end and moved by said rocker bar, and means for supporting the opposite end of said ash grate adapted to cause a downward movement of said end as said grate is reciprocated by said rocker bar.
- 20 26. In a furnace, the combination of a series of inclined grate bars, an ash grate at the lower ends of said bars to receive ash and clinker therefrom, a rocker bar for supporting and operating the lower ends of the grate bars and one end of the ash grate, and pivotal means for supporting the opposite end of the ash grate.
- 25 27. In a furnace, the combination of a series of inclined grate bars, an ash grate at the lower ends of said bars to receive ash and clinker therefrom, a rocker bar for supporting and operating the lower ends of the grate bars and one end of the ash grate, and links pivotally connected to said ash grate for supporting the opposite end thereof and adapted to permit a rising and falling movement thereof.
- 30 28. In a furnace, the combination of a series of inclined grate bars, an ash grate at the lower ends of said bars to receive ash and clinker therefrom, a rocker bar for supporting and operating the lower ends of the grate bars and one end of the ash grate, a link pivotally attached at one end to said ash grate for supporting the same at its free end, a pivoted arm connected to the opposite end of said link, and manually operable means for turning said arm.
- 35 29. In a furnace, the combination of a series of inclined grate bars, an ash grate at the lower end of said bars to receive ash and clinker therefrom, a rocker bar having a longitudinal rib engaging the grate bars to operate the same, ears on the rocker bar to which the ash grate is pivotally attached at one end to be supported and actuated thereby, and means for pivotally supporting the opposite end of said ash grate.
- 40 30. In a furnace, the combination of a series of inclined grate bars, an ash grate at the lower end of said bars to receive ash and clinker therefrom, a rocker bar having a longitudinal rib engaging the grate bars to operate the same, ears on the rocker bar to which the ash grate is pivotally attached at one end to be supported and actuated thereby, a shaft, an arm on said shaft extending beneath the ash grate, a link connecting the end of said arm and the opposite end of said ash grate to pivotally support the same, means for manually turning said shaft and power operated means for turning the rocker shaft.
- 45 31. In a furnace, the combination of a series of hollow inclined grate bars having open upper ends and each having an opening in its lower side near its lower end, a deflector in each bar opposite each opening in the lower side thereto to deflect air passing through the bar, into the end portion of the bar, a wind box having a wall forming a support for the upper ends of said grate bars, an air chamber below the grate bars into which the openings near the lower ends of said bars open, a stationary twyer inclosing the upper open ends of the grate bars and forming a passage connecting said ends directly with the wind box, and means for operating the grate bars.
- 50 32. In a furnace, the combination of a retort extending into said furnace, and a twyer detachably engaged with a side wall of said retort and comprising a plurality of sections having laterally projecting portions to provide air passages between the said sections, said passages leading to the side of the twyer forming a continuation of said retort wall, and a plurality of hollow grate bars movably supported with their ends opening into said twyer.
- 55 33. In a furnace, a twyer formed of a series of blocks comprising a plurality of vertically extending sections secured together, each section having a wall formed with openings, a web extending inwardly from said wall, and ribs on the web adapted to meet adjacent sections and form air passages between the sections leading to said openings, a series of hollow grate bars supported with their upper ends opening into and movable within said twyer, and means for imparting motion to said grate bars.
- 60 In testimony whereof I affix my signature in the presence of two witnesses.

WILFRED A. HARE.

Witnesses:

ANNA M. DORR,
CHAS. W. STAUFFIGER.
